(57) **CLAIM**

What is claimed is the ornamental design for a vent cap, as shown and described.

DESCRIPTION

FIG. 1 is a three-quarter isometric view of an embodiment of a vent cap design of the present invention;
FIG. 2 is a top plan view of the vent cap design of FIG. 1;
FIG. 3 is a front side view of the vent cap design of FIG. 1;
FIG. 4 is back side view of the vent cap design of FIG. 1;
FIG. 5 is a right side view of the vent cap design of FIG. 1;
FIG. 6 is a left side view of the vent cap design of FIG. 1;
FIG. 7 is a bottom view of the vent cap design of FIG. 1;
FIG. 8 is a three-quarter isometric view of an embodiment of a vent cap design of the present invention;
FIG. 9 is a top plan view of the vent cap design of FIG. 8;
FIG. 10 is a front side view of the vent cap design of FIG. 8;
FIG. 11 is back side view of the vent cap design of FIG. 8;
FIG. 12 is a right side view of the vent cap design of FIG. 8;
FIG. 13 is a left side view of the vent cap design of FIG. 8;
FIG. 14 is a bottom view of the vent cap design of FIG. 8;
FIG. 15 is a three-quarter isometric view of an embodiment of a vent cap design of the present invention;
FIG. 16 is a top plan view of the vent cap design of FIG. 15;
FIG. 17 is a front side view of the vent cap design of FIG. 15;
FIG. 18 is back side view of the vent cap design of FIG. 15;
FIG. 19 is a right side view of the vent cap design of FIG. 15;
FIG. 20 is a left side view of the vent cap design of FIG. 15;
and,
FIG. 21 is a bottom view of the vent cap design of FIG. 15.
